United States Patent Office.

WARREN RICHARDSON, OF COLFAX, CALIFORNIA.

Letters Patent No. 90,959, dated June 8, 1869.

IMPROVEMENT IN DEVICE FOR TURNING SAW-LOGS.

The Schedule referred to in these Letters Patent and making part of the same.

To all whom it may concern:

Be it known that I, WARREN RICHARDSON, of Colfax, county of Placer, State of California, have invented an Adjustable Sliding Block for Saw-Mills; and I do hereby declare the following description and accompanying drawings are sufficient to enable any person skilled in the art or science to which it most nearly appertains, to make and use my said invention or improvement without further invention or experiment.

My invention relates to a new and improved device for canting saw-logs, after they have been faced by the saw on one side, and require to be turned, so that the remaining sides may also be faced; and, in fact, it is used to slide the log or stick being sawed to its place on the carriage, at any stage of the sawing, where care is to be exercised to prevent splitting or injury to the edges or corners of the stick.

To more fully illustrate and explain my invention, reference is had to the accompanying drawings, forming a part of this specification, of which—

Figure 1 is a sectional elevation.

Figure 2 is a plan.

Similar letters of reference in each of the figures indicate like parts.

I first construct a solid and substantial frame, composed of the bottom timbers M, upper timbers S, and cross-timbers O, capable of supporting the weight of the heaviest logs.

The upper timbers S are provided with mortises, which extend from the front end to near their middle, and pass entirely through the timbers. The lower timbers are also mortised directly beneath the mortise in the upper timbers, and are, in fact, a continuation of the same.

In these mortises I place blocks B B, the upper ends of which are bevelled to an incline, the lower portion of the incline being towards the front of the carriage or frame.

These blocks are arranged to slide up and down by means of eccentrics I I, placed on a shaft, C, which passes across the lower part of the frame.

When lowered, the upper ends of the incline blocks are on a level with the upper face of the timbers S S, thus being entirely out of the way, so as to allow the logs to be rolled along over the frame and placed upon the carriage. The lower ends of the blocks upon which the eccentrics operate, are cut in a circle, so as to give as much bearing-surface as possible upon the eccentrics.

The frame is set near the carriage upon which the logs are placed, and at right angles to it, and the logs are first rolled over it and on to the carriage previous to sawing. One side of the log is then placed or sawed off, and the carriage run back to its former position.

The next step to be taken is to turn the log, so as to bring another side to the saw, in order that it may be squared previous to sawing it into lumber; and this is done by raising the blocks B B, so as to present an inclined plane upon which the log may be placed, by merely turning it over, so that the side already faced will fall upon the blocks, after which it can easily be slid back to its place upon the carriage, in the proper position for taking off the slabs from the other sides.

The device is especially useful and convenient for canting the log into position upon the carriage while sawing it into scantlings or square timbers, as, when it has been sawed of the proper width in one direction, and it is desired to turn it, all that is necessary is to lower the blocks B B, and, as the log is sawed, it is moved over upon the front ends of the timbers S.

The shaft C is then turned by means of a belt-connection, bevel-gear, or other device operated by the power which runs the mill.

This causes the eccentrics I I to raise the blocks B B, and consequently the timbers, giving it a pitch or incline, when, by the use of dog-hooks, it may be canted into the proper position for cutting it in the opposite direction.

The usual manner of canting the logs to their position on the carriage is to place wedges under them, which consumes much time, and is very laborious; while, with my device, the logs can be handled with great ease and celerity.

Having thus described my invention,

What I claim, and desire to secure by Letters Patent, is—

The blocks B B, sliding vertically in mortises, and having bevelled tops, in combination with the eccentrics I I and shaft C, the whole being constructed and arranged substantially as and for the purpose set forth.

In witness whereof, I have hereunto set my hand and seal.

WARREN RICHARDSON. [L.S.]
